US00D557340S

(12) **United States Design Patent** (10) Patent No.: **US D557,340 S**
(45) Date of Patent: **** Dec. 11, 2007**

(54) **CONTAINER FOR GLUE**

(75) Inventors: **Yoshio Nagahama**, Itami (JP); **Eizo Kajigaki**, Takatsuki (JP)

(73) Assignee: **Taoka Chemical Co., Ltd.**, Osaka (JP)

(**) Term: **14 Years**

(21) Appl. No.: **29/256,513**

(22) Filed: **Mar. 22, 2006**

(30) **Foreign Application Priority Data**

Feb. 7, 2006 (JP) 2006-002640

(51) **LOC (8) Cl.** **19-06**

(52) **U.S. Cl.** **D19/66**

(58) **Field of Classification Search** D19/66, D19/67, 68, 69, 70; 156/523, 527, 540, 577; 206/411; 225/6, 25, 39, 77; 242/588, 588.1, 242/588.2, 588.3, 588.6, 598.5

See application file for complete search history.

(57) **CLAIM**

The ornamental design for a “container for glue,” as shown and described.

DESCRIPTION

FIG. 1 is a perspective view of the design;

FIG. 2 is a front elevational view of the design;

FIG. 3 is a rear elevational view of the design;

FIG. 4 is a side elevational view of one side of the design;

FIG. 5 is a side elevational view of the other side of the design;

FIG. 6 is a plan view of the top of the design;

FIG. 7 is a plan view of the bottom of the design; and,

FIG. 8 is an exploded perspective view of the design.

The broken lines connecting the container and cap in FIG. 8 form no part of the claimed design.
